UNITED STATES PATENT OFFICE.

FREDERICK GORMAN, OF OKEMAH, OKLAHOMA.

TILE-MOLD.

958,628.

Specification of Letters Patent. Patented May 17, 1910.

Application filed July 27, 1909. Serial No. 509,831.

To all whom it may concern:

Be it known that I, FREDERICK GORMAN, a citizen of the United States, residing at Okemah, in the county of Okfuskee and 5 State of Oklahoma, have invented a new and useful Tile-Mold, of which the following is a specification.

It is the object of the present invention to provide an improved construction of mold, 10 and the invention relates more specifically to that class of molds which are designed for use in molding drain tiles and the like, and one aim of the invention is to provide a mold of this type so constructed as to mold 15 each tile with a flange at one end and a rabbet at the other end, whereby the tiles may be fitted end to end in a water-tight manner.

It is a further object of the present invention to provide a mold construction of such 20 character that the mold sections may be readily assembled and disassembled without danger of injuring or defacing the tile being molded.

Other novel features of the invention and 25 structural details embodying advantages will be pointed out and understood from the specific description which is to follow.

In the accompanying drawings:—Figure 1 is a vertical sectional view through a mold 30 constructed in accordance with the present invention. Fig. 2 is a detail perspective view of the outer wall of the mold, the sections thereof being shown in assembled relation. Fig. 3 is a similar view of the base 35 of the mold. Fig. 4 is a perspective view of one of the sections of the outer wall of the mold. Fig. 5 is a view similar to Fig. 2, illustrating the core of the mold, the sections thereof being in assembled relation. Fig. 6 is a perspective view in detail of the 40 head of the mold upon which the core is assembled. Fig. 7 is a perspective view in detail of one of the sections of the core of the mold. Fig. 8 is a perspective view of one 45 of the bands for disposal about the core of the mold. Fig. 9 is a similar view of the strip which is disposed against the mold core and closes the space between those sections 50 of the core between which the wedge blocks are inserted.

In the drawings the mold is illustrated as set upon a base, which is indicated by the 55 numeral 10, and is supported upon sills 11. The base 10 is formed centrally with an opening indicated by the numeral 12, and, upon its upper surface is further formed or

provided with an upstanding flange 13, which is continuous, and may be annular, rectangular, or of other outline.

It will be observed, from an inspection of 60 Fig. 3 of the drawings, that the opening 12 in the base 10 of the mold is concentric with respect to the flange 13, and the function of this construction will presently be fully explained. 65

It will be understood of course that by assembling the several sections comprising the mold wall, about the upstanding annular flange 13, upon the upper surface of the base 10, the sections are not only held in 70 proper relative position, but also in centered relation and against lateral slipping or sliding.

The mold proper embodies in its structure 75 an outer wall and a core, and this outer wall is made up of a number of sections, each of which is indicated by the numeral 14. Each of these sections 14 is preferably comprised of a number of staves, which are secured together in arcuate relation, and the several 80 sections, when assembled, form a cylindrical mold wall, as will be appreciated from an inspection of Fig. 2 of the drawings.

It will be understood that while the mold 85 sections are herein shown and described as of arcuate form, and the completed mold wall as of cylindrical form, these sections may have other forms, or, in other words, the mold wall may be rectangular, if desired, depending, of course, upon the form 90 of title it is desired to manufacture.

In setting up the mold, the sections 14 are assembled upon the base about the flange 13 thereon, and, when properly assembled, 95 hoops 15 are fitted over the assembled sections, and circumscribe the walls at the upper and lower ends thereof, these hoops being clearly shown in Fig. 2 of the drawings, and one of the hoops being shown in perspective directly above this figure, as if 100 about to be disposed or fitted upon the assembled sections.

The mold proper further embodies a core, 105 which is disposed within the mold wall, or, rather, is surrounded by it, and between which and the said wall the cement or other material from which the tiles are to be molded, is poured. This core is illustrated in Fig. 5 of the drawings, and, like the mold wall, is built up of a number of assembled 110 sections, and each of these sections is indicated by the reference numeral 16, the sec-

tions being substantially identical with the sections 14 of the mold wall, except that they are of smaller dimensions.

In assembling the sections 16 of the core 5 of the mold, they are disposed edge to edge, as in the case of the sections 14 of the mold wall, and are held in such relation through the medium of a band 17, fitted upon the core at the lower end thereof, and a band 18, 10 fitted upon the core at the upper end thereof, this latter band carrying an outstanding flange 19, of substantially the same thickness as the flange 18, but of smaller diameter.

In order that the sections of the core may 15 be held expanded to the full extent, there are fitted between the opposing edges of two of the sections 16 of the core, one at the upper and the other at the lower end thereof, wedges, indicated by the numeral 20, these 20 wedges being driven into place after the bands 17 and 18 have been disposed upon the core. Inasmuch as the insertion of these wedge blocks between the opposing edges of the sections as above described will serve to 25 space the said edges, a sheet metal plate or strip 21 is provided, which is disposed against the outer surface of the core and is engaged at its ends by the bands 17 and 18, whereby it is held firmly in place in position 30 to close the space between the said edges. This band is clearly shown in perspective in Fig. 9 of the drawings.

In order that the core may be held in centered relation with respect to the wall of the 35 mold when the mold is set up and in condition to be filled, there is provided a head 22, which is circular in outline and is fitted in the opening 12 in the base 10 of the mold, this head having an upstanding enlargement 23 upon its upper face, which also is concentric with respect to the opening 12. This upstanding enlargement 23 upon the head 22 is of the same diameter as the interior diameter of the core of the mold, and, 40 45 as will be readily understood, the mold core sections are built or assembled around this enlargement and upon that portion of the upper face of the head 22 which lies beyond the peripheral edge of the enlargement. In order to support the head 22 in position in 50 the opening 12, there is provided a cleat 24, which is slidably and removably mounted upon the under side of the base 10, as clearly shown in Figs. 1 and 3 of the drawings, it

being understood that, by moving this cleat, 55 the head normally supported thereby will drop through the opening 12, to permit of collapse of the core, or rather of the sections thereof.

In using the mold, the core sections are 60 first assembled upon the head 22 and about the enlargement 23 thereon, and the wall sections are then assembled upon the base 10 about the upstanding flange 13 thereon. After this has been done, the plastic mate- 65 rial from which the tiles are to be manu- 70 factured is poured into the space between the outer surface of the core and the inner surface of the wall and is allowed to set and harden. After the material has become suf- 75 ficiently hard to permit of dismounting of the mold, the wall sections are first removed from around the tile, after which the cleat 24 is removed, allowing the head 22 to drop beneath the base, whereupon the wedges 20 75 are driven out from between the opposing edges of the sections comprising the core, and the core sections are collapsed and removed.

What is claimed is:—

In a mold, a base having an upstanding annular flange, a plurality of mold sections assembled about said flange, said base being formed also with an opening concentric with respect to the flange, a head fitted in 85 said opening and having a circular upstanding enlargement, a plurality of mold core sections assembled upon said head about the enlargement thereon, wedge blocks inserted between certain of said sections whereby to 90 expand the same in assembled relation, means fitting about the sections for holding the same in such relation, said sections, at their upper ends, being provided with an outstanding annular flange, a strip fitted 95 against the sections and closing the space between those sections between which the wedge blocks are inserted, and means removably supported beneath the base for supporting the head within the opening. 100

In testimony that I claim the foregoing as my own, I have hereto affixed my signature in the presence of two witnesses.

FREDERICK GORMAN.
